DESIGN FOR A TABLE

George H. Mildwoff, New York, N. Y.

Application July 4, 1942, Serial No. 107,424

Term of patent 3½ years

To all whom it may concern:

Be it known that I, George H. Mildwoff, a citizen of the United States of America, residing in New York city, county of New York, and State of New York, have invented a new, original, and ornamental Design for a Table, of which the following is a specification, reference being had to the accompanying drawing, forming part thereof.

The figure on the drawing is a front perspective view of a table, showing my new design. The opposite side presents substantially the same appearance as the side shown.

I claim:

The ornamental design for a table, substantially as shown and described.

GEORGE H. MILDWOFF.
